Primary Examiner — Wan Laymon*(74) Attorney, Agent, or Firm* — Evan Feldstein**(57) CLAIM**

I claim the ornamental design for a menstrual cup, as shown and described.

DESCRIPTION

FIG. 1 is a perspective view of a menstrual cup.

FIG. 2 is a top view of the menstrual cup.

FIG. 3 is a bottom view of the menstrual cup.

FIG. 4 is a left side view of the menstrual cup.

FIG. 5 is a right side view of the menstrual cup.

FIG. 6 is a front view of the menstrual cup; and,

FIG. 7 as a rear view of the menstrual cup.

The broken lines are directed to environment and are for illustrative purposes only; the broken lines form no part of the claimed design.

1 Claim, 7 Drawing Sheets(56)
